UNITED STATES PATENT OFFICE.

HENRY WILLIAM WAGENET, OF OAKLAND, CALIFORNIA.

COLLAPSIBLE WARDROBE.

Application filed November 16, 1922. Serial No. 601,324.

To all whom it may concern:

Be it known that I, HENRY WILLIAM WAGENET, a citizen of the United States, and a resident of Oakland, county of Alameda, State of California, have invented a new and useful Collapsible Wardrobe, of which the following is a specification.

The present invention relates to improvements in portable wardrobes and its particular object is to introduce a collapsible feature that will allow the wardrobe to be folded to resemble in shape an ordinary suitcase. The wardrobe when unfolded is of sufficient dimensions to comfortably accommodate various clothes suspended from hangers in the ordinary manner so as to allow the clothes to maintain their shape and to be carried from place to place without requiring pressing before they may be used. A wardrobe of this character, however, is too large to be carried conveniently and for this purpose I introduce a feature allowing the wardrobe to be doubled on itself into a form in which it may be carried conveniently. Since baggage of a travelling man is usually carried for very short distances only, as for instance, when moving from the train to the hotel, or from the hotel to the train, the wardrobe will remain in its folded condition for a short time only, and this is not sufficient to affect the shape of the clothes since the wardrobe can be returned to its normal condition immediately upon arrival at the hotel room or at the train, when the clothes will again be freely suspended from their hangers and straighten themselves out.

The preferred form of my invention is shown in the accompanying drawing in which Figure 1 represents a side view of my portable wardrobe; Figure 2 a vertical section through the same along line 2-2 of Figure 1; Figure 3 an end view showing the wardrobe in its collapsed condition; and Figures 4 and 5 vertical cross sections respectively of two parts forming the wardrobe. While I have shown only the preferred form of the invention, it should be understood that various changes or modifications may be made within the scope of the claims hereto attached without departing from the spirit of the invention.

My wardrobe consists principally of the rectangular box (1) and a cover (2) for the same, box and cover being of substantially similar shape, but the cover being slightly

larger so that it may be telescoped on the box. The box is split preferably along a horizontal center line as shown at (3) and hinged as shown at (4) so as to allow the upper portion (6) to fold on the lower portion (7). This box when standing on edge as shown in the drawing is sufficiently large to accommodate various clothes, such as men's or ladies' suits which may be freely suspended from hangers (8) adapted to be secured in the top of the box by means of hooks (9) or any other suitable means.

The cover (2) is split along the same horizontal plane as the box to form two portions (11) and (12) and is hinged as shown at (13), the hinge being preferably arranged so as to align with the hinge (4) when the cover is in its place. The top of the cover is provided along the line of the split with flaps (14) and (16) extending in opposite directions and adapted to lie flat against the other portion when the cover is in the normal position shown in Figure 4, and to cover the gap in the device created by the folding of the same, as shown in Figure 3. The flaps terminate in suitable handles (17) by means of which the whole wardrobe may be carried in its folded condition. The box itself is preferably provided with a flap (18) adapted to cover the hinge (4) so as to prevent injury to the clothes from getting caught in the hinge.

The wardrobe is used as follows: It is normally held in the position shown in Figure 1 and the clothes are suspended from the hangers (8) to depend freely as they would in any ordinary closet or wardrobe. Whenever possible the wardrobe should be held in this position whether the owner is travelling on the train or stopping in a hotel room. Only when the owner has to actually handle the wardrobe, that is, carry it from place to place, he folds the same on itself into the position shown in Figure 3, when the dimensions of the wardrobe will not exceed that of any ordinary suitcase.

I claim:

1. In a portable wardrobe a box split centrally so as to form two symmetrical portions and hinged to allow one portion to fold on the other one, and a cover for the box made to divide along an operative line when the wardrobe is folded.

2. In a portable wardrobe a box split centrally so as to form two symmetrical portions and hinged to allow one portion to fold

on the other one, and a cover for the box made to divide along an operative line when the wardrobe is folded, having flaps along said line for covering the gap created by the 5 folding operation.

3. In a portable wardrobe a box split centrally so as to form two symmetrical portions and hinged to allow one portion to fold on the other one, and a cover for the box made 10 to divide along an operative line when the wardrobe is folded, having flaps along said line for covering the gap created by the folding operation, and handles on said flaps facilitating the carrying of the folded wardrobe.

4. In a portable wardrobe a box split centrally so as to form two symmetrical portions and hinged to allow one portion to fold on the other and a cover adapted to be telescoped over the box, the cover being split 15 and hinged to divide along an operative line when the wardrobe is folded.

5. In a portable wardrobe a box split centrally so as to form two symmetrical portions and hinged to allow one portion to fold on the other and a cover adapted to be telescoped over the box, the cover being split 20 and hinged to divide along an operative line when the wardrobe is folded, and having flaps along said line for covering the gap created by the folding operation.

6. In a portable wardrobe a box split centrally so as to form two symmetrical portions and hinged to allow one portion to fold on the other and a cover adapted to be telescoped over the box, the cover being split 25 and hinged to divide along an operative line when the wardrobe is folded, and having flaps along said line for covering the gap 30 created by the folding operation, and handles on said flaps facilitating the carrying of the folded wardrobe.

HENRY WILLIAM WAGENET
